No. 831,988.

PATENTED SEPT. 25, 1906.

J. G. PLATT & W. B. LANDON.
CHEMICAL FIRE EXTINGUISHER.

APPLICATION FILED SEPT. 28, 1905.

UNITED STATES PATENT OFFICE.

JOHN G. PLATT AND WILLIAM B. LANDON, OF MEADVILLE, PENNSYLVANIA, ASSIGNORS OF ONE-THIRD TO MORRIS B. BREWSTER, OF COLUMBUS, OHIO.

CHEMICAL FIRE-EXTINGUISHER.

No. 831,988.

Specification of Letters Patent.

Patented Sept. 25, 1906.

Application filed September 28, 1905. Serial No. 280,407.

To all whom it may concern.

Be it known that we, JOHN G. PLATT and WILLIAM B. LANDON, citizens of the United States, residing at Meadville, in the county 5 of Crawford and State of Pennsylvania, have invented certain new and useful Improvements in Chemical Fire-Extinguishers, of which the following is a specification.

Our invention relates to new and useful 10 improvements in chemical fire-extinguishers.

The object of the invention is to provide a superior device and greatly simplify the construction, thus increasing the commercial value.

15 Another object lies in the provision whereby the bottle may be filled without removing it from its support or disturbing the stopper-valve.

Still another feature resides in the arrangement of the parts whereby the acid is mixed 20 with the liquid at the proper point and in such quantities as to assure a slow mixture, thereby avoiding the danger of explosion and preventing any of the acid escaping from 25 the reservoir without first mixing with the liquid.

Finally, the object of the invention is to provide an extinguisher that will be strong, durable, and efficient, comparatively inexpensive to manufacture, and one in which the several parts will not be liable to get out 30 of working order.

With the above and other objects in view the invention consists of the novel details of 35 construction and operation, a preferable embodiment of which is described in the specification and illustrated in the accompanying drawings, wherein—

Figure 1 is a vertical sectional view of the 40 extinguisher, showing the stopper-valve and acid-bottle in elevation. Fig. 2 is a similar view, the extinguisher being inverted and the acid-bottle broken away to illustrate its connection with the cover; and Fig. 3 is a 45 horizontal cross-sectional view taken on the line $x-x$ of Fig. 1, a portion of the extinguisher being shown in plan.

In the drawings the numeral 1 designates a cylindrical reservoir formed of a suitable 50 metal and having its entire inner surface

coated with a suitable acid-resisting metal, such as lead. An annular base 2 is provided on the reservoir below its bottom 3, while a bail-handle 4 is arranged in the base for purposes hereinafter described.

At its upper end the reservoir is provided with an annular externally-screw-threaded collar 5, on one side of which a bail-handle 6 is secured to the reservoir. A short curved pipe 7 extends from the upper end of the reservoir adjacent the collar 5 and opposite the handle 6. On its end the pipe is provided with a nozzle 8, directed downwardly, while about the entrance to the pipe 7 a wire strainer 9 is secured to the inner side of the reservoir. An annular cover 10, having a depending internally-threaded flange 11, is provided for the reservoir and has its flange 11 engaging with the collar 5. The cover 10 is formed near one side with a vertical cylindrical valve-chamber 12, the upper end of which is closed by a screw-cap 13, applied from the upper outer side of the cover, so that access to the valve-chamber may be had by simply unscrewing the cap 13 and without disturbing the cover 10. At its lower end 75 the chamber is formed with an annular valve-seat 14, on which the enlarged head of a valve-stopper 15 is adapted to rest, the said valve-stopper projecting some distance 80 below the valve-chamber and adapted to work therein by gravity. A curved passage 16 leads from the valve-chamber a short distance above the valve-head, (reference being had to Fig. 1,) extending through the cover 85 and establishing communication with the under side thereof. About the lower end of the curved passage the cover is formed with an annular recess 17, (see Fig. 2,) which recess is adapted to snugly receive the mouth 90 of a glass bottle 18 in such a manner that the opening in the neck of the bottle registers with the passage 16. The bottle, which is adapted to contain the acid, is held rigidly in place, so as to form a tight joint with the 95 cover by a holder comprising a horizontal plate 19, extending across the bottom of the bottle, and rods 20, secured to the plate and extending on opposite sides of the bottle, have their upper ends threaded into the cover 100.

10 on each side of the passage 16. By provision of such a holder the bottle is securely held in place irrespective of the position of the reservoir.

5 In utilizing the extinguisher the operator grasps the bail-handle 4 at the bottom of the extinguisher in one hand and the handle 6 in the other, inverting the reservoir, so that the nozzle 8 is pointed upwardly, as shown in Fig. 2. In this manner he is enabled to readily manipulate the extinguisher and to direct the stream therefrom wherever desirable, while the use of a hose is advantageously dispensed with, the latter often causing trouble by becoming twisted and increasing the excitement and confusion of the operator. When the reservoir is inverted, the stopper-valve, 15 falls by gravity in the valve-chamber 12, so that its head rests on the cap 13, and the acid contained in the bottle 18 is free to pass through the curved passage 16 into the valve-chamber 12, past the reduced end of the valve, and into the reservoir, where it mixes with the liquid solution contained therein, 20 forming the proper chemical extinguishing liquid, which passes through the strainer 9, pipe 7, and out of the nozzle 8 with great force. Owing to the curved passage 16 the acid will pass very slowly from the bottle, so 25 that it is properly mixed when coming in contact with the solution contained in the reservoir. In fact, were it not for the chemical action resulting from the contact of the acid with the solution which tends to draw the acid from the bottle only a few drops of the acid would pass from the bottle at a time. 30 From this it will be apparent that the possibility of the acid passing out of the pipe 7 without mixing with the solution is reduced to a minimum and the proper mixture necessarily had. Should it be desirable to discontinue the use of the extinguisher, the same upon being inverted or returned to its original position will immediately cease to operate, as 35 the stopper-valve falling in the chamber 12 will close the said valve-chamber and prevent communication between the same and the reservoir.

40 Much stress is placed upon the cap 13, the valve-chamber 12, and the passage 16, whereby the acid-bottle may be readily filled by simply removing the cap 13 and pouring the acid into the valve-chamber 12, from which it will pass by way of the passage 16 to the bottle 18, the stopper-valve preventing any of the acid passing into the reservoir. This may be accomplished without removing the cover 10 or in any way disturbing the bottle. It is also to be noted that the valve-chamber 45 and bottle-holder being supported from the cover 10 by simply removing the cover the parts may be withdrawn from the reservoir and the same filled or cleaned without dis-

turbing the acid-bottle or its parts. However, should it ever be desirable to remove the acid-bottle 18 it is simply necessary to loosen the rods 20 and the bottle may be readily disengaged from the cover.

50 It is to be observed that owing to the curved formation of the passage 16 upon returning the reservoir to its normal or original position, as shown in Fig. 1, the acid will immediately cease to pass from the bottle to the reservoir and also any acid remaining in the said passage will pass back into the bottle, as 55 is clearly evident from the drawings. Therefore should the stopper-valve fail to operate and close on the valve-seat 14 further mixture of the acid with the solution, as by absorption, is reduced to a minimum.

55 Having now fully described our invention, what we claim, and desire to secure by Letters Patent, is—

1. In a fire-extinguisher, the combination with a reservoir and an acid-bottle, of a cover for the reservoir carrying a valve-chamber, said cover being arranged to establish communication between the acid-bottle and the valve-chamber, and a valve arranged in the chamber.

60 2. In a fire-extinguisher, the combination with a reservoir, of a closure for the reservoir carrying a valve-chamber, and an acid-bottle supported at one side of the valve-chamber and having communication therewith.

65 3. In a fire-extinguisher, the combination with a reservoir, of a closure for the reservoir carrying a valve-chamber, an acid-bottle supported at one side of the valve-chamber and having communication therewith, and a valve arranged in the chamber adapted to cut off communication with the reservoir.

70 4. In a fire-extinguisher, the combination with a reservoir, of a closure for the reservoir carrying a valve-chamber, an independent closure for the valve-chamber, and an acid-bottle supported at one side of the valve-chamber and having communication therewith.

75 5. In a fire-extinguisher, the combination with a reservoir, of a closure for the reservoir carrying a valve-chamber, an acid-bottle supported from the closure at one side of the valve-chamber and having communication therewith, and a valve arranged in the valve-chamber.

80 6. In a fire-extinguisher, the combination with a reservoir, of a closure for the reservoir carrying a valve-chamber, an independent closure for the valve-chamber arranged to permit access to the valve-chamber from the exterior of the reservoir-closure, and an acid-bottle arranged in the reservoir having communication with the valve-chamber.

85 7. In a fire-extinguisher, the combination with a reservoir, of a cover for the reservoir

carrying a valve-chamber and provided with an internal passage having communication with the valve-chamber, an acid-bottle having communication with the passage, means for supporting the acid-bottle from the cover, a cap for the valve-chamber, and a valve arranged in the valve-chamber.

In testimony whereof we affix our signatures in presence of two witnesses.

JOHN G. PLATT.

WILLIAM B. LANDON.
